[57] **CLAIM**

The ornamental design for a water metering apparatus for a coffee maker or similar article, as shown and described.

DESCRIPTION

FIG. 1 is a perspective view of the water metering apparatus for a coffee maker or similar article showing my new design with the spout in extended position;

FIG. 2 is a left side elevational view thereof, with the spout in retracted position and not visible;

FIG. 3 is a right side elevational view thereof, with the spout in retracted position and not visible;

FIG. 4 is a rear elevational view thereof;

FIG. 5 is a front elevational view thereof, with the spout in retracted position and visible; and

FIG. 6 is a top plan view thereof, with the spout in retracted position and not visible; and

FIG. 7 is a bottom plan view.
